(57) **CLAIM**

We claim the ornamental design for an automotive vehicle rear spoiler with a central stop light, as shown and described.

DESCRIPTION

FIG. 1 is a rear perspective view of an automotive vehicle rear spoiler with a central stop light, of the new design; FIG. 2 is rear perspective view thereof; FIG. 3 is a top view thereof; FIG. 4 is a rear view thereof; FIG. 5 is a side view thereof; FIG. 6 is a side view thereof, opposite that of FIG. 5; FIG. 7 is a bottom view thereof; and, FIG. 8 is a front view thereof.
The broken lines (including for example, the wheels, the rear lift gate, the rear fascia, the back window, the roof, and the rear quarter panel) are for environmental illustrative purposes only and form no part of the claimed design. The dotted lines in FIGS. 7 and 8 indicate that the portions of the rear spoiler internal to the periphery are not part of the claimed design.
